US00D421924S

United States Patent

[19]

Luo et al.

[11] Patent Number: Des. 421,924

[45] Date of Patent: ** Mar. 28, 2000

[54] **THERMOCOUPLE MODULE**

[75] Inventors: **Ji Lie Luo; Deng Wei Shu**, both of Shenzhen, China

[73] Assignee: **Precision Mastech Enterprises Company**, Kwun Tong, The Hong Kong Special Administrative Region of the People's Republic of China

[**] Term: **14 Years**

[21] Appl. No.: **29/100,766**

[22] Filed: **Feb. 18, 1999**

[51] LOC (6) Cl. **10-04**

[52] U.S. Cl. **D10/49; D10/78**

[58] Field of Search D10/49, 50, 52, D10/78; 324/537; 374/142, 170, 179, 181, 208; 136/221, 230
